CLAIM

The ornamental design for a container in the shape of a rabbit, as shown and described.

DESCRIPTION

FIG. 1 provides a front perspective view of a container in the shape of a rabbit.

FIG. 2 provides a front view of a container in the shape of a rabbit.

FIG. 3 provides a rear view of a container in the shape of a rabbit.

FIG. 4 provides a left side view of a container in the shape of a rabbit.

FIG. 5 provides a right side view of a container in the shape of a rabbit.

FIG. 6 provides a top view of a container in the shape of a rabbit; and,

FIG. 7 provides a bottom view of a container in the shape of a rabbit.

The broken lines showing connectors for the lid, rim, and interior are for illustrative purposes only and form no part of the invention.
